UNITED STATES PATENT OFFICE.

HENRY E. SPECK, OF DES MOINES, IOWA.

SLIDING DOOR.

1,206,607.

Specification of Letters Patent. Patented Nov. 28, 1916.

Application filed June 13, 1916. Serial No. 103,454.

To all whom it may concern:

Be it known that I, HENRY E. SPECK, a citizen of the United States, residing at Des Moines, in the county of Polk and State of Iowa, have invented certain useful Improvements in Sliding Doors, of which the following is a specification, reference being had therein to the accompanying drawing.

10 The present invention relates to improvements in sliding doors, and relates more particularly to a weather strip carried upon the lower edge thereof and rendered adjustable so as to prevent the passage of air beneath the door at all times.

15 A further object of this invention is the provision of a weather stop or strip for sliding doors, which is simple, durable and inexpensive in construction and thoroughly efficient and practical in use.

20 In the accompanying drawings:—Figure 1 is a front elevation of a sliding door and its support carrying the present weather stop or strip. Fig. 2 is a perspective view 25 of the lower edge of the door, showing one end of the stop or strip removed to clearly show the recess in the door for accommodating the roller of the strip.

25 Referring to the drawings, the numeral 30 5 designates the door which is provided with the two hangers 6 for engagement with the flanged runway or support 7 which is attached to the frame structure 8 which is supported upon the sill or floor 9.

35 Formed in the lower inner corners at the bottom of the door are roller receiving recesses 10, while attached for oscillating and vertical sliding movement upon one face of the door upon the lower edge thereof is the

weather stop or strip 11, provided with the two slots 12 for the reception of the studded or headed fastening members 13 carried by the door. Also carried by the strip upon the face adjacent the door at the corners thereof are the two rollers 14 which are adapted to 45 be incased in the recesses of the door when the stop is in its uppermost position.

It will thus be seen that when the present door is being moved upon its supporting rail, that the present weather stop or strip 50 will accommodate itself to the contour of the floor or sill and will thus project below the door to prevent the passage thereby of the air, thus producing an exceedingly desirable weather stop or strip for a sliding 55 door.

What I claim as new is:

1. The combination with a sliding door provided with recesses in the two lower corners thereof, of a weather stop or strip slidably attached to one face adjacent the lower edge of the door and having supporting rollers for movement into and out of said recesses.

2. The combination with a sliding door 65 provided with recesses in the two lower corners thereof, of a weather stop or strip slidably attached to one face adjacent the lower edge of the door and having supporting rollers for movement into and out of said 70 recesses, said strip being provided with a plurality of transversely disposed elongated slots, and a studded fastening means fitting in each slot and attached to the door for securing the stop to the door for sliding 75 movement.

In testimony whereof I affix my signature.
HENRY E. SPECK.
